DIXON LEWERS, OF LOUISVILLE, KENTUCKY, ASSIGNOR TO FERGUSON
& LEWERS, OF SAME PLACE.

Letters Patent No. 72,648, dated December 24, 1867.

IMPROVEMENT IN STAVE-MACHINE.

The Schedule referred to in these Letters Patent and making part of the same.

TO WHOM IT MAY CONCERN:

Be it known that I, DIXON LEWERS, of Louisville, Jefferson county, State of Kentucky, have invented a new and useful Stave-Machine; and do hereby declare the following to be a full, clear, and exact description thereof, reference being had to the accompanying drawings, making part of this specification.

This invention relates to a machine for forming at one operation the convex outer and concave inner side of staves for casks, tubs, barrels, &c.

Figure 1 is a partially-sectionized elevation of a stave-machine embodying my invention.

Figure 2 is a horizontal section taken at the line X X, fig. 1.

Figure 3 is an enlarged section through the line Y Y, fig. 2.

A is a horizontal bench or way, upon which the rough stave is placed, and along which it is pushed and guided in the act of planing. B is the stave-pusher or driver, caused to advance and recede along the bench A, (the receding motion being about twice as fast as the advancing motion,) by the following means: C is the driving-shaft, carrying a fly-wheel, D, whose stud or wrist d is provided with a dove-tailed head, E, which occupies a corresponding slot, f, in a revolving arm, F, whose shaft f' is eccentric to the driving-shaft C, aforesaid. A consequence of this eccentricity is that the head E rotating the arm F, travels toward and from the centre thereof, once during each rotation, causing an alternate acceleration and retardation of the rotation, as before stated. The other end of the shaft f' carries an arm, G, having a dove-tailed slot, g, provided with a wrist, H, capable of being secured at any desired distance from the centre of rotation of said arm, according to the desired stroke of the driver. The wrist H is connected to one end of a pitman, I, and the other end of said pitman is attached to the rear end of the driver B by means of another wrist, J. K and L are two stationary knives, which serve to reduce the stuff to a definite width and thickness. M M' are guide-strips, which hold the stave to a rectilinear path. N N' N'' N''' are rollers, which are caused, by means of springs O, attached to their housings n, to hold the stuff with a downward but yielding pressure. A portion of the bench is excavated at a, to receive the blades p of a rounding-cutter, P, journaled athwart and beneath the bench. Journaled longitudinally over the bench, in housings R, slotted r, so as to be adjustable in height, is a hollowing cutter-head, S.

I claim herein as new, and of my invention—

The stave-pusher or driver B, when operated by the wheel D, head E, revolving slotted arm F, shaft f', arm G, and pitman I, or their equivalents, substantially as and for the purpose set forth.

In testimony of which invention, I hereunto set my hand.

DIXON LEWERS.
